CHRISTOPHER PEEL, OF NEW YORK, N. Y.

FIRE-ESCAPE.

SPECIFICATION forming part of Letters Patent No. 629,205, dated July 18, 1899.

Application filed June 3, 1899. Serial No. 719,206. (No model.)

To all whom it may concern:

Be it known that I, CHRISTOPHER PEEL, of the city of New York, borough of Manhattan, in the county and State of New York, have invented new and useful Improvements in Fire-Escapes, of which the following is a full, clear, and exact description.

This invention relates to fire-escapes of a type employing a platform or the like at an elevated window and a ladder for descent therefrom.

The object of my invention is to provide a fire-escape of the type indicated which is foldable between two upper windows of a building and is capable of release from folded adjustment to automatically assume operative position, affording convenient and safe means for escape to the ground from either or both of the windows.

20 The invention consists in the novel construction and combination of parts, as is hereinafter described, and defined in the claims.

Reference is to be had to the accompanying drawings, forming a part of this specification, in which similar characters of reference indicate corresponding parts in all the figures.

Figure 1 is a side elevation of a portion of a building and a front view of the fire-escape in folded condition thereon. Fig. 2 is a like view of the building and a front view of the fire-escape opened out and ready for service. Fig. 3 is a sectional plan view of the device in partially-opened condition, substantially on the line 3 3 in Fig. 2. Fig. 4 is a vertical transverse sectional view of the device opened out, taken substantially on the line 4 4 in Fig. 2. Fig. 5 is an enlarged sectional plan view of the fire-escape folded, taken substantially on the line 5 5 in Fig. 1; 40 and Fig. 6 is an enlarged sectional plan view of details, substantially on the line 6 6 in Fig. 3.

In the illustration of the improvement and its application to a building for service, A indicates the vertical side of a building, and B B two adjacent windows therein spaced apart, as usual. Between the windows B B is placed the novel fire-escape device, which will now be described.

50 Two rectangular metal plates 7 of like dimensions are provided, having a border-flange 7^a bent at a right angle on each edge of the

plate, thus giving a box-like form to each one. The pieces 7 are strongly hinged upon the building side wall, each near the side of the 55 casement of a window B, said hinged connections a being so arranged that when in opened adjustment a border-flange on each piece 7 will have contact with the building-wall, and thus adapt the remaining portion of 60 the same to project outwardly at a right angle to said wall, as clearly shown in Fig. 3. The plates 7 may be designated "guard-walls" and in height reach near the tops of the windows B, while their lower portions project somewhat below said windows. A rectangular aperture of considerable size is cut in each guard-wall 7, having greater dimension lengthwise of the plate it is formed in than transversely of the same, each aperture a' in the 65 guard-walls affording a passage-way therethrough when the guard-walls are in opened condition. A rectangular plate-metal platform or foot-board 8 is provided for each guard-wall 7, said foot-boards being hinged at their lower ends, respectively, upon the inner sides of the guard-walls 7 at the apertures a' and having such relative dimensions 70 that when in folded condition they will each cover the aperture opposite which they are arranged. Each foot-board 8 is furnished with two wing-walls 9 9^a, these being respectively hinged by one edge, so as to be adapted to stand upright at the outer side and outer end of the foot-board when the latter is 75 horizontally disposed, or, in other words, folded outward and downward from the aperture a', normally closed by the wing-walls. The guard-walls 7 are each provided with a coiled 80 spring appliance 7^b, which is so connected thereto that it will exert force to project the guard-wall when unrestrained outward from the building-wall, and spring-hinges b are provided for each foot-board 8 where it is 85 jointed upon the guard-wall to which it is 90 complementary.

Spring-hinges c are employed to joint the wing-walls 9 9^a each upon the foot-boards 8, and the end wing-walls 9^a respectively contact with the adjacent ends of the side wing-walls 9. A suitable degree of concave curvature is given to each end wing-wall 9^a upon its inner side opposite and near one end of the side wing-wall with which it coacts, and 95 100

said end of the side wing-wall is convexly curved to correspond with the convexity of the end wing-wall.

It will be seen that when both wing-walls 5 9^a on each foot-board 8 are erect the act of folding the end wing-wall 9^a inwardly will so press upon the convex edge of the side wing-wall as to cause it to fold inwardly beneath the end wing-wall. In order to arrest the 10 unfolding movement of each end wing-wall 9^a and side wing-wall 9 when they are free to move under stress of their spring-hinges c, short slots d are cut in the edge portions of each foot-board 8 opposite the hinges, and 15 the latter are secured to the foot-boards inside, but near said slots.

A tongue e is projected from the edge of a wing-wall below or outside of each hinge-joint, which tongues rock into respective slots 20 d when the wing-walls 9^a are permitted to unfold, and the unfolding action of each spring-hinge c will be arrested when the wing-walls 9^a stand upright at edges of the foot-boards 8.

On the outer end of each unfolded foot-board 8 one end g of a flexible connection 10 is secured, and thence said flexible connection (preferably a metal cord or chain) extends through the aperture a' of a respective guard-wall 7 over small loose pulleys h, and 30 thence through a perforation or thimble i in the building-wall A to have the remaining end secured upon a reel 11, held on the wall of the room, into which the flexible connections 10 are introduced.

35 A plate-spring 7^b is attached upon the upper portion of each guard-wall 7 and projects outwardly through the aperture a' of said wall to have spring-pressure upon the upper end of an end wing-wall 9^a when the foot-boards are folded, so as to enter said apertures.

40 It will be evident if the fire-escape is in opened condition, as shown in Fig. 2, that the foot-boards 8 will be projected across the building-wall A in opposite directions just below the window B each is thrown in front of, and as a support for each foot-board a bracket-arm 12 is secured on the window-sill or wall adjacent thereto, so that said arms will lie directly below the horizontally-disposed foot-boards and aid the spring-hinges c in sustaining weight imposed upon the foot-boards. If the fire-escape is closed and is 45 held by the ratchet-and-pawl device m m', it will appear as a box between the windows B, and it may be protected from rust by enamel or paint.

50 In Figs. 2 and 3 there is shown a pendent ladder 13, hung or secured upon the wall A of the building between the windows B, which ladder in complete form extends near to the pavement or ground. Spaced ladder-rungs 14 may be secured above the ladder 13 on the wall A to afford handholds for persons about to descend the ladder.

55 In case it becomes necessary to use the fire-escape it is but the work of a moment to detach the pawl m' of the ratchet-wheel m, which

will permit the strong springs 7^d to throw the guard-walls 7 outwardly and hold them in parallel planes at the sides of the windows B. Simultaneously with the outward movement of the guard-walls 7 the tension of the plate-springs 7^b projects the foot-boards 8 downwardly until they are disposed horizontally in front of the windows B, the spring-hinges 75 of the wing-walls 9^a at the same time raising these walls, which serve to prevent timid persons or children from accidentally falling off of the foot-boards while passing over them through the passage-ways a' in the guard-walls 7 to reach the ladder-rungs 14 and then descend the ladder 13.

60 To fold the fire-escape into box form, it is only necessary that the reel 11 be turned in the right direction, so as to wrap up the flexible connections 10, which will first fold up the foot-boards 8 until the plate-springs 7^b have pressure upon the end wing-walls 9^a and fold them, as well as the side wing-walls 9, which will be effected when the foot-boards 90 are flush with the guard-walls 7 and occupy the apertures a' in the latter. A continuation of the rotary movement of the reel 11 will pull the guard-walls 7 toward the building-wall A and finally close one box-like 95 guard-wall over the other one, as clearly shown in Fig. 5.

65 As all portions of the device are formed of metal, heat will not affect the stability of any part of the same, so that it affords a safe 100 means of escape from a burning building.

In case there is fire in one of the rooms having a window B, toward which the foot-board of an adjacent guard-wall 7 falls when the reel 11 is released, it is contemplated to prevent flame or smoke from interfering with the use of the fire-escape through the remaining opened window B by pulling upon the flexible connection 10, that is fastened to the foot-board in front of the window which is 110 unsafe to escape from, so as to raise this foot-board and close the aperture a' in the guard-wall it is hung upon, so that smoke or flame will be prevented from reaching persons using the ladder that is approached from the other 115 window.

Having thus described my invention, I claim as new and desire to secure by Letters Patent—

1. The combination with an upright ladder 120 on a building-wall, of foldable guard-walls above the ladder and adjacent to the windows of the building, said walls each having a foot-board foldable over an aperture thereof, and adapted for projection beneath a window, when the guard-walls are adjusted outwardly from the building-wall. 125

2. The combination with an upright ladder on a building-wall and held between two windows of the building, of two spring-pressed guard-walls hinged upon the building-wall, each adjacent to one of the windows and disposed above the ladder, two foot-boards each 130 spring-pressed to project outward from an

aperture in a respective guard-wall and fall beneath a window, and means to compactly fold the guard-walls and foot-boards from within the building.

- 5 3. The combination with an upright ladder on a building-wall and held between two windows of the building, of two spaced box-like guard-walls hinged on the building-wall and spring-pressed to open at a right angle thereto, two foot-boards hinged to fold over oblong apertures formed in the guard-walls, and spring-pressed to open out at a right angle thereto, two wing-walls hinged on the side and end edges of each foot-board and each 15 spring-pressed to open at a right angle thereto, and a flexible connection extending from each foot-board which will fold the foot-boards and also fold the guard-walls, when pulled upon from within the building.
- 20 4. The herein-described fire-escape, essentially comprising two guard-walls held to swing out from a building-wall between two

windows therein, each guard-wall having an oblong aperture or passage-way therein, a foot-board hinged by one end upon each 25 guard-wall and spring-pressed to project at a right angle thereto, an end wing-wall and a side wing-wall, spring-hinged upon each foot-board so as to fold inwardly, a plate-spring at the aperture in each guard-wall, 30 and adapted to impinge upon the wing-walls of a foot-board to fold them when said foot-board is folded to cover the aperture in the guard-wall it is opposite, a flexible connection fastened to the outer end of each foot-board and thence extended within the building, and means to shorten said connections and thus fold the wing-walls, foot-boards and guard-walls between the windows.
